(57) **CLAIM**

I claim the ornamental design for a phial retainer for liquid medicine mixer, as shown and described.

DESCRIPTION

FIG. 1 is a top and front perspective view of a phial retainer for liquid medicine mixer of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines shown represent unclaimed subject matter and form no part of the claimed design. Additionally, the unevenly broken lines in FIG. 1 define the limits of the claimed design.
